Attorney

UNITED STATES PATENT OFFICE.

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed September 16, 1924, Serial No. 737,961. Renewed July 17, 1926.

This invention relates to typing upon continuous work-webs, particularly to means in a typewriting machine for gaging and severing typed form-sections of continuous work-webs, and for collating other work-forms with reference to the web-forms preparatory to typing.

In mail-order houses it is customary to prepare an invoice to cover each order of merchandise shipped. The preparation of the invoice is begun upon receipt of the order by typing the name and address of the customer in an address space provided on the invoice-form. The invoice-form is then removed from the typewriter and is later completed when the order has been filled by entering other data.

In accordance with the present invention, provision is made of means for expediting the typing of the names and addresses on these invoice-forms. The invoices, connected end to end, in the form of a continuous web, are led into a typewriting machine for the typing of the names and addresses.

A web-severing knife is mounted at the delivery side of the platen to sever the leading form, when typed, from the remainder of the web, and provision is made of means for adjusting the knife toward and from the line of writing, so that it may be located to register with the line of division between the first and second forms of the web when the address space of the second form is in writing position. This relation is important because it enables the work to be positioned at one operation for severing of the finished form and for typing of the new form. The knife-adjusting means preferably consists of mounts for the knife having numerous pairs of threaded openings, any of which pairs may receive screws for supporting the knife. By this means, the knife can be instantly located in parallelism with the writing line and will be positively supported without liability of slipping out of place under the pull of tearing-off operations. The mount openings are spaced over a sufficient range to enable the knife to be positioned in the desired relation for various forms of invoices having their address spaces differently located.

A leading-edge gage is adjustable to a

position exactly a form-length in advance of the adjustable knife, so that the drawing of the leading edge of the web to the gage will locate the line of division between the first and second forms in register with the knife. This also locates the second form in position for typing. The leading-edge gage serves thus both as a severing gage and a work collating or positioning gage, locating the web at a single operation in position for severing the first form and for beginning the typing upon the second form.

When it is desired to change from one form of invoice to another, it is only necessary to adjust the knife in accordance with the length of heading of the new form, so that the address space of the form, having its leading edge in register with the knife, will be located at the printing point, and to adjust the leading-edge gage to exactly a form-length in advance of the adjusted knife.

When an address has been typed, the feed-rolls of the machine are cast off and the invoice-web is drawn forward to the leading-edge gage. For the purpose of preventing skewing of the work in such advance, provision is made of a side-edge gage at the delivery side of the platen and side gages at the introductory side of the platen. The gage at the delivery side of the platen is adjustably mounted for different widths of work, upon the severing knife, provision being made of a series of threaded openings in the knife, any one of which may receive a gage-attaching screw. This side gage extends downward from the knife through the plane of a front paper-table adjacent the knife, and the front paper-table is slotted to accommodate the gage in its various adjusted positions.

In addition to the typing of the invoice forms, it is also necessary to provide an address-label in connection with each order. A feature of the invention relates to the provision of means for collating one or more address-labels over the invoice-form in the machine, so that the address may be typed at a single operation upon the address-label and the invoice. To this end, provision is made of a front aligning plate, having leading and side edge gages, and this aligning

plate is mounted upon the web-severing knife with provision for adjustment toward and from the line of writing, and angularly with reference thereto. With the invoice-web drawn forward to the leading-edge gage, and with the feed-rolls cast off, the address-label is inserted downward at the front of the platen and is squared and collated with reference to the gaged web by means of the aligning plate. The feed-rolls are then made effective to hold the web for severing and to feed the web and address-slip afterward for typing.

Other features and advantages will herein-after appear.

In the accompanying drawings,

Figure 1 is a fragmentary front elevation of a typewriting machine embodying the present invention.

Figure 2 is a longitudinal vertical section on the line 2—2 of Figure 1.

Figure 3 is a longitudinal vertical section on the line 3—3 of Figure 1.

Figure 4 is a fragmentary perspective view showing the web-severing knife and the aligning plate mounted thereon.

Figure 5 is a diagrammatic view showing the collated relation of the leading invoice-form and address-slip.

The machine comprises a cylindrical platen 10 journaled by an axle 11 in the ends 12 of a platen-frame 13 forming part of a traveling carriage 14, as is usual in the Underwood standard typewriter. The continuous invoice-web 15, which may be carried by a shaft 16 mounted upon the carriage 14 in the manner disclosed in my application, Serial No. 626,282, filed March 20, 1923, (now Patent No. 1,586,715, dated June 1, 1926), is led, between adjustable side guides 17, down around the platen beneath feed-rolls 18, and thence upward over a front paper-table 19 carried by brackets 20 upon the ends 12 of the platen-frame.

A web-severing knife 21 is secured by screws 22 upon mounts 23 carried by the brackets 20, provision being made in the mounts of series of threaded openings 24 arranged in pairs to receive the knife-securing screws 22 for supporting the knife in parallelism with the writing line of the machine. The screw-receiving openings 24 extend through a considerable range so that the knife 21 can be positioned to register with the leading edges of various invoice-forms when said forms have their address spaces in writing position. A leading-edge gage 25 is adjustable along a gage-bar 26 that extends upwardly from the middle of the front paper-table 19, and may be secured in any desired position upon the gage-bar by means of a binding screw 27. The leading-edge gage 25 may thus be located a form-length in advance of the adjusted knife 21, so that, upon the completion of the typing

of a form-section of the invoice-web 15, the web may be positioned at a single operation for the tearing off of the first form-section which has been typed, and for the typing of the second form-section.

Prior to the advance of the web to the leading-edge gage, the feed-rolls 18 are cast off by the usual means (not shown). During this advance, it is important that the web 15 be maintained square with the platen. This result is obtained, in part, by cutting away the front paper-table 19 as seen at 28, so that the operator may grasp the web 15 close down to the knife 21 and draw it forward with his hand contacting the gage-bar 26 all the way. The gage-bar 26 thus serves as a guide for the operator's hand in advancing the web. Provision is also made of a left edge-gage 29 for the web at the delivery side of the platen to co-operate with the side-edge gages 17 at the introductory side of the platen in keeping the web 15 straight. This gage 29 is mounted upon the knife 21, being secured by a screw 30 in any opening of a series of threaded openings 31 in the knife, according to the width of the web. The gage 29 extends downward through the plane of the front paper-table 19, and the front paper-table is provided with a slot 32 to accommodate the gage in its various adjusted positions.

At the same time that the invoice covering an order is addressed, it is desired to address also a shipping label 33 for the goods. Provision is accordingly made of means for collating the shipping label with reference to the invoice-web at the time that the web is drawn forward to the leading-edge gage, the web being positioned at this time with the address space of the second form at the printing point, and the feed-rolls being cast off. To this end, an aligning plate 34, having a leading-edge gage 35 and a side-edge gage 36 for positioning the address-label, is mounted upon the knife 21 with provision for adjustment toward and from the writing line, and for angular adjustment to bring the leading-edge gage 35 into parallelism with the writing line. The knife 21 has ears 37 extending downwardly from it, and these ears have slots 38 for receiving shouldered screws 39 that support the aligning plate 34. The aligning plate may be secured in any desired position by adjusting these shouldered screws 39 along the slots 38, and then turning knurled finger-nuts 40 fast upon the screws.

The machine is used in the following manner: The first form having been typed, the feed-rolls 18 are cast off, and the web 15 is drawn forward to the leading-edge gage 25. This locates the line of division between the first and second forms in register with the edge of the knife 21 for tearing off, and at the same time locates the address space.

of the second form in writing position. The tearing off cannot be effected, however, until the feed-rolls 18 have been restored. An address-slip 33, or a pack of address-slips, with interleaved carbons, is inserted downward at the front of the platen prior to the restoration of the feed-rolls 18, and is collated over the second invoice-form by means of the gages 35 and 36 of the aligning plate 34. The carriage may be caused to pass to the right of the right margin-stop if desired to facilitate the front insertion of the address-slip. The feed-rolls 18 are then restored, the leading form-section is torn off, and the typing of the form-section at the printing point, together with the superposed collated address-slip, is begun.

Should it become necessary to change the invoice-web for one having invoice-forms of a different length and having the address spaces differently located, the machine can be quickly accommodated to the change by adjusting the knife to register with the leading edge of the new form when the address space thereof is at the printing point, and by then adjusting the leading-edge gage a form-length in advance of the knife.

Variations may be resorted to within the scope of the invention, and portions of the improvements may be used without others.

Having thus described my invention, I claim:

1. In a typewriting machine, the combination with a platen and writing instrumentalities, of a knife for severing web-sections, means for adjusting the knife toward and from the platen to position it in registration with the leading edge of a web-form having its first writing line at the line of writing of the machine, and a leading-edge gage adjustable to position it a form-length in advance of the knife, the arrangement being such that the leading-edge gage is effective simultaneously to locate the leading web-form for severing and the second web-form for typing.

2. In a typewriting machine, the combination with a platen and writing instrumentalities, of a knife for severing web-sections, a front paper-table for supporting the web in proximity to the knife, a gage-bar extending upward from the middle of the front paper-table, and a leading-edge gage on the gage-bar to locate the web for severing, the front paper-table being cut away at its upper middle portion to admit the hand of the operator all the way down to the knife, so that the operator may use the gage-bar to guide his hand straight forward throughout the entire advance of the web to the leading-edge gage.

3. In a typewriting machine, the combination with a platen and writing instrumentalities, of a knife for severing typed web-sections, a front paper-table for supporting

the web in proximity to the knife, a leading-edge gage to which the web may be drawn to position it for severing, and means for guiding the web squarely in its advance to the leading-edge gage, comprising side-guiding means at the introductory side of the platen, and a side gage at the delivery side of the platen, said side gage at the delivery side of the platen being mounted on the knife and extending toward the front 75 paper-table therefrom.

4. In a typewriting machine, the combination with a platen and writing instrumentalities, of a knife for severing typed web-sections, a front paper-table for supporting 80 the web in proximity to the knife, a leading-edge gage to which the web may be drawn to position it for severing, and means for guiding the web squarely in its advance to the leading-edge gage, comprising side-guiding means at the introductory side of the platen, and a side gage at the delivery side of the platen, said side gage being adjustably mounted on the knife and extending through the plane of the front paper-table, the front paper-table being slotted to accommodate the side gage in its various adjusted positions.

5. In a typewriting machine, the combination with a platen and writing instrumentalities, of a knife for severing typed web-sections, a front paper-table for supporting the web in proximity to the knife, and a side gage for the web mounted on the knife and extending toward the front paper-table 100 therefrom.

6. In a typewriting machine, the combination with a platen and writing instrumentalities, of a knife for severing typed web-sections, a front paper-table for supporting the web in proximity to the knife, a side gage for the web mounted on the knife and extending toward the front paper-table therefrom, the knife having numerous openings for positioning the gage, and means for co-operating with any one of said openings to secure the gage upon the knife.

7. In a typewriting machine, the combination with a platen and writing instrumentalities, of a knife for severing typed web-forms, the knife being located to register with the line of division between the first and second web-forms when the second web-form is in first writing line position, a leading-edge gage for locating the web at a single 115 operation in position for severing the first form and for typing the second form, and means for collating a separate work-sheet with reference to the gaged web.

8. In a typewriting machine, the combination with a platen and writing instrumentalities of a knife for severing typed web-forms, the knife being located to register with the line of division between the first and second web-forms when the second web-form is 120 130

in first writing line position, a leading-edge gage for locating the web at a single operation in position for severing the first form and for typing the second form, and an aligning plate mounted on the knife and having side and leading-edge gages for collating a separate work-sheet with reference to the gaged web.

9. In a typewriting machine, the combination with a platen and writing instrumentalities, of a knife for severing typed web-forms, the knife being located to register with the line of division between the first and second web-forms when the second web-form is in first writing line position, a leading-edge gage for locating the web at a single operation in position for severing the first form and for typing the second form, an aligning plate mounted on the knife for collating a separate work-sheet with reference to the gaged web, and means for adjusting the aligning plate toward and from the writing line of the machine.

10. In a typewriting machine, the combination with a platen and writing instrumentalities, of a front paper-table, a leading-edge gage for positioning a work-sheet on the table in writing position, an aligning plate-support above the table, and a work-collating table in the form of an aligning plate mounted on the support and having an edge gage for positioning another work-sheet outside the first in position for typing the first line thereon.

11. In a typewriting machine, the combination with a platen and writing instrumentalities, of a front paper-table, a web-severing knife above the front paper-table and in proximity thereto, a leading-edge gage for gaging the web for severing, a front aligning plate for collating an outside work-sheet with reference to the gaged web, aligning plate-supports on the knife extending downward toward the writing line therefrom, and means for securing the aligning plate in various positions on the supports.

12. In a typewriting machine, the combination with a platen and writing instrumentalities, of a front paper-table, a leading-edge gage for positioning a work-sheet on the table in writing position, an aligning plate-support over-hanging the table, a work-collating table in the form of an aligning plate mounted on the support and having an edge gage for positioning another work-sheet relatively to the first, and means for adjusting the aligning plate edgewise angularly or bodily.

13. In a typewriting machine, the combination with a revoluble platen, of feed-rolls co-operating with the platen to feed a work-web and to hold it stationary for severing, means for casting off the feed-rolls to permit the work-web to be drawn forward

rapidly for gaging, a knife mounted above the platen to have its blade register with the leading edge of a web-form when the first writing line thereof is at the printing point, a leading-edge gage located a form-length in advance of the knife to position the web at a single operation for severing of the first form and for typing the first line of the second form, and an aligning plate for collating a separate work-web with reference to the work-web after the work-web has been gaged and prior to the restoration of the feed-rolls.

14. In a typewriting machine, the combination with a platen and writing instrumentalities, of adjustable means for severing web-sections, means for simultaneously positioning the web-form for severing the typed web-section and for typing the next web-section, and adjustable means for positioning separate work-sheets on said latter web-section to be concurrently typed therewith.

15. In a typewriting machine, the combination with a platen and writing instrumentalities, of means for severing web-sections, adjustable means for positioning the severing means in various positions parallel with the writing line of the machine, means for simultaneously positioning the web-form for severing the typed web-section and for typing the next web-section, means for positioning separate work-sheets on said latter web-section to be concurrently typed therewith, and adjustable means for securing said last-named positioning means on the severing means in various positions parallel therewith.

16. In a typewriting machine, the combination with a platen and writing instrumentalities, of means for severing web-sections, adjustable means for positioning the severing means in various positions parallel with the writing line of the machine, means for simultaneously positioning the web-form for severing the typed web-section and for typing the next web-section, means for positioning separate work-sheets on said latter web-section to be concurrently typed therewith, and means for securing said last-named positioning means on said severing means in various positions parallel therewith and ahead of the same.

17. In a typewriting machine, the combination with a platen and writing instrumentalities, of a front paper-table for supporting a web, a knife for severing typed web-sections, adjustable means for supporting the knife on said table in various positions parallel with the writing line of the machine, an aligning plate, and adjustable means for supporting said plate on said knife in various positions parallel therewith.

18. In a typewriting machine, the combination with a platen and writing instrumentalities,

talities, of a front paper-table for supporting a web, a knife for severing typed web-sections, adjustable means for supporting the knife on said table in various positions parallel with the writing line of the machine, an aligning plate, adjustable means for supporting said plate on said knife in various

positions parallel therewith and ahead of the same, and means for simultaneously positioning the web-form for severing the typed web-section and for typing the next web-section.

JESSE A. B. SMITH.
